(57) CLAIM

The ornamental design for a tablet stand, as shown and described.

DESCRIPTION

FIG. 1 is a perspective view of a tablet stand showing the claimed design;

FIG. 2 is another perspective view thereof;

FIG. 3 is yet another perspective view thereof;

FIG. 4 is an elevational view of a first face thereof;

FIG. 5 is an elevational view of a second face thereof;

FIG. 6 is a side view of one side thereof;

FIG. 7 is a side view of the opposite side of FIG. 6 thereof;

FIG. 8 is a view looking down upon the first and second faces thereof; and,

FIG. 9 is an elevational view of a third face thereof.

The subject matter in broken lines forms no part of the claim.
